(57) **CLAIM**

I claim the ornamental design for an auxiliary port and outlet extender, as shown and described.

DESCRIPTION

FIG. 1 is a top perspective view of an auxiliary port and outlet extender, showing a first embodiment of my new design;
FIG. 2 is a bottom perspective view of FIG. 1;
FIG. 3 is a front elevational view of FIG. 1;
FIG. 4 is a rear elevational view of FIG. 1;
FIG. 5 is a left-side elevational view of FIG. 1, the right-side elevational view being a mirror image thereof;
FIG. 6 is a top plan view of FIG. 1;
FIG. 7 is a bottom plan view of FIG. 1;
FIG. 8 is a top perspective view of a second embodiment thereof;
FIG. 9 is a bottom perspective view of FIG. 8;
FIG. 10 is a front elevational view of FIG. 8;
FIG. 11 is a rear elevational view of FIG. 8;
FIG. 12 is a left-side elevational view of FIG. 8, the right-side elevational view being a mirror image thereof;
FIG. 13 is a top plan view of FIG. 8;
FIG. 14 is a bottom plan view of FIG. 8;
FIG. 15 is a top perspective view of a third embodiment thereof;
FIG. 16 is a bottom perspective view of FIG. 15;
FIG. 17 is a front elevational view of FIG. 15;
FIG. 18 is a rear elevational view of FIG. 15;
FIG. 19 is a left-side elevational view of FIG. 15, the right-side elevational view being a mirror image thereof;
FIG. 20 is a top plan view of FIG. 15;
FIG. 21 is a bottom plan view of FIG. 15;
FIG. 22 is a top perspective view of a fourth embodiment thereof;
FIG. 23 is a bottom perspective view of FIG. 22;
FIG. 24 is a front elevational view of FIG. 22;
FIG. 25 is a rear elevational view of FIG. 22;
FIG. 26 is a left-side elevational view of FIG. 22, the right-side elevational view being a mirror image thereof;
FIG. 27 is a top plan view of FIG. 22; and,
FIG. 28 is a bottom plan view of FIG. 22.
The broken lines showing a wall, a portable electronic device, a top port adapter, power plugs, power sockets and outlet borders in the figures depict environmental matter and form no part of the claimed design.
